UNITED STATES PATENT OFFICE.

JOSEPH F. MAY, OF UTICA, NEBRASKA.

WATERING-TROUGH.

SPECIFICATION forming part of Letters Patent No. 443,647, dated December 30, 1890.

Application filed July 29, 1890. Serial No. 360,299. (No model.)

To all whom it may concern:

Be it known that I, JOSEPH F. MAY, a citizen of the United States, residing at Utica, in the county of Seward and State of Nebraska, 5 have invented a new and useful Watering-Trough, of which the following is a specification.

This invention has relation to improvements in stock-watering troughs; and the objects in view are to provide such a trough as will prevent an overflow of the same with water and will maintain the water on a level or at a proper height at all times, regardless of the quantity taken therefrom or consumed 15 by the stock.

With the above objects in view the invention consists in certain features of construction hereinafter specified, and particularly pointed out in the claim.

Referring to the drawings, Figure 1 is a perspective of a watering-trough constructed in accordance with my invention. Fig. 2 is a vertical longitudinal section of the same. Fig. 3 is a detail in perspective of the float. Fig. 25 4 is a similar view of the valve. Fig. 5 is a detail view showing more clearly the attachment of the float to the valve.

Like numerals of reference indicate like parts in all the figures of the drawings.

30 1 designates an ordinary rectangular trough, one-half of which is covered by a cover or lid 2, screwed or otherwise secured in position upon the trough. The inner edge of the lid 2 is provided with a depending partition 3, 35 which extends down to within a short distance of the bottom and subdivides the trough into a rear water-receiving compartment 4 and a front drinking-space 5, which is crossed by a transverse strip 6, in order to prevent hogs 40 from getting into the trough with their feet in the act of drinking.

An opening 7 is formed in the rear wall of the trough, and a pipe or hose 8 leads therefrom to any suitable elevated source of supply. The inner face of the rear wall at the 45 point opposite the opening has secured thereto a perforated plate 9, through the perforations of which are passed screws, by which the plate is held in position. The plate is also 50 provided with a central valved opening or

seat 10, which registers with the opening 7. Secured to the plate by means of a screw 11 is an inwardly-opening clack-valve 12, adapted to cover the seat of the valve-plate, and provided upon its exterior surface with an 55 outwardly-disposed lug 13.

14 designates a float, in this instance rectangular in shape, and provided at its rear edge with eyes 15, which loosely engage hooks 16, extending from the inner surface of the 60 rear wall. The rear edge of the float is provided with a re-enforcing plate 17, which comes in contact with the lug when said float is in a horizontal position, which indicates the high-water mark, and thus the valve is 65 closed against its seat.

From the above it will be apparent that water may enter the trough and continue to flow therein until it reaches such a height as to elevate the float to a horizontal position, 70 at which time the valve will be entirely closed by reason of the rear end of the plate pressing the same upon its seat. If a small quantity of water is consumed and withdrawn from the trough, the float is lowered slightly and 75 the valve proportionately opened, so that the exact quantity drawn is admitted to the trough, and thus the same is always maintained full or at a proper level, and the possibility of any waste is positively avoided. 80

It will be observed that the plate 9, the valve 12, and the float are all connected and form an article adapted to be applied to the side wall of a trough or barrel simply by the insertion of the four screws 11 through the 85 openings of the plate 9. In a similar manner the float and valve mechanism may be withdrawn for the purpose of cleaning the trough. I also avoid any complicated construction and any pivotal joints liable to become inoperative by the rust, &c. 90

Having thus described my invention, what I claim is—

The combination, with the trough having an opening in one of its vertical walls, and a 95 supply-pipe leading thereto and from a source of supply, of a metal plate secured to said walls and provided with a valve-seat opposite the opening in the wall and below the seat with hooks, the flexible valve secured at 100

its upper end to the plate above its seat and provided with a lug, and a float provided at its lower inner edge with eyes which engage the hooks of the plate, whereby it is loosely hinged to the plate below the valve and its seat, said float being adapted when elevated to abut at its upper rear end against the lug of the valve, substantially as specified.

In testimony that I claim the foregoing as my own I have hereto affixed my signature in presence of two witnesses.

JOSEPH F. MAY.
